UNITED STATES PATENT OFFICE

2,429,036

ARTICULATED BRACELET OR THE LIKE

Ingemar Taegtstroem, Waterbury, Conn., assignor of one-third to Madison D. Pickens, New York, N. Y.

Application August 30, 1946, Serial No. 694,025

19 Claims. (Cl. 59—79)

1

The invention relates to articulated bracelets or the like and, in particular, to the provision of new and improved articulated structures adapted particularly to wrist-bands, bracelets, watch-bands, necklaces, chains, or similar articles or devices made up of a plurality of members, elements or links pivotally or flexibly connected together in end-to-end relation, which links, or some at least thereof, are readily and conveniently detachable one from the other manually, without recourse either to actual or simulated tools or devices.

It is an object of this invention to provide such an improved construction embodying a link particularly adapted to the performance of its desired function, wherein the manually operable means for detaching the respective links is readily and conveniently accessible at all times to the wearer of a bracelet, band or chain embodying the construction of this invention, wherein the aforesaid means is so incorporated in the link structure as to impart decorative value thereto, rather than to detract from the decorative or aesthetic appearance thereof, and wherein the aforesaid means is so located and of such form as to prevent accidental actuation thereof and consequent undesirable uncoupling of the bracelet.

It is a further object of this invention to provide such link constructions embodying an expansion feature whereby a bracelet or similar structure embodying the link construction is expansible and contractible during the wearing thereof, and wherein the expansion thereof is positively limited in order to prevent damage to the links upon application of undue expanding forces to the structures.

It is a further object of this invention to provide such a construction wherein the utmost flexibility of assembly is achieved, and wherein the links may move transversely with respect to one another, as well as expansibly and pivotally.

It is a further object of this invention to provide such a construction which lends itself to cheap and convenient production in various materials which may be molded, stamped, or otherwise formed, by the method most suitable for working the particular material.

These and other objects and advantages will clearly appear from the following description taken with the drawing and the appended claims.

In the drawing:

Fig. 1 is a plan view of a bracelet embodying the construction of this invention with two of the links disconnected from one another, in order

2

to open the closed band formed by the links when all are coupled together;

Fig. 2 is a perspective view of one of the links shown in Fig. 1, with the top plate or wall removed, in order to disclose the internal structure thereof;

Fig. 3 is a plan view of the structure shown in Fig. 2, and showing the manner in which a pair of adjacent links are connected thereto, with the parts shown in the position taken thereby when the assembly is contracted and with one link biasing spring omitted in the interest of clearness of disclosure;

Fig. 4 is a view similar to Fig. 3, but showing the parts in the position assumed thereby when the assembly is extended to the ultimate degree and illustrating the positive connecting link expansion stop means in operation;

Fig. 5 is a view similar to Fig. 3, but showing both connecting link biasing springs in place, and illustrating the position taken by the parts when manual force is applied laterally for retracting the plungers and uncoupling the link from an adjacent link for opening the band or bracelet formed by the assembly;

Fig. 6 is an end view of a complete link shown in Fig. 1, looking in the direction indicated by the arrows 6—6, in Fig. 1;

Fig. 7 is a section taken substantially on the line 7—7 of Fig. 3;

Fig. 8 is a similar section taken substantially on the line 8—8 of Fig. 3;

Fig. 9 is a section taken substantially on the line 9—9 of Fig. 4;

Fig. 10 is a similar section taken substantially on the line 10—10 of Fig. 4;

Fig. 11 is an enlarged fragmentary detailed view in perspective, partially broken away, showing a modification wherein the link engaging connections or trunnions are formed integrally with an end wall of a link casing;

Fig. 12 is a plan view of a simplified modification according to this invention;

Fig. 13 is a side view of the structure shown in Fig. 12, as seen from the right looking toward the left;

Fig. 14 is a view similar to Fig. 12, of a modification of the structure therein, with the link parts in the position assumed by them when an assembly formed thereof is contracted;

Fig. 15 is a view similar to Fig. 14, but showing the structure of Fig. 14 in the position assumed thereby when the assembly is expanded, and when adjacent links are displaced transversely with respect to one another; and

3

Fig. 16 is a plan view similar to Fig. 3 of another, simplified, modification, according to this invention.

Referring to the drawing in detail, Fig. 1 illustrates a band formed of eight links, according to this invention, wherein the links are designated, respectively, A, B, C, D, E, F, G and H, and wherein the links A and H are uncoupled from one another. When the links A and H of the structure shown in Fig. 1 are connected or coupled together, a closed wristlet, band, or bracelet is formed thereby. Each of the links in the assembly shown in Fig. 1 is capable of being manually connected and disconnected from the adjacent links in a manner which will hereinafter clearly appear.

Each of the links A—H comprises a rectangular frame or casing, generally designated 20, of rectangular form, as shown in Figs. 1 to 11 inclusive, wherein the top or outer wall is formed by the top plate 21 and the similar side walls 22 and end walls 23 and 24 are integral with the inner or bottom wall 25. The similar side walls 22 are each cut away throughout their length, to form a slot 26 (Figs. 2 and 11) extending from end wall 23 to end wall 24. The end wall 23 is provided with a pair of laterally spaced rectangular slots or apertures 27, permitting extension of a pair of connecting arms outwardly of the wall 23 for movement transversely toward and away from one another as and for a purpose which will hereinafter appear.

Slidable between the end walls 23 and 24, toward and from one another, are a pair of similar, obverse plungers 28, of generally rectangular form, each provided at its inner ends with a pair of similar spring receiving slots 29. A pair of compression springs 30 are disposed between the inner ends of the plungers 28, each with one of two aligned slots 29 supporting its opposite ends.

The compression springs 30 constantly bias or yieldingly urge the plungers 28 apart to the extent limited by a shoulder (not shown) formed between the thick inner end portion of each plunger 28 and the manually engageable outer end portion 31 thereof which is of reduced thickness. Intermediate the thick, inner end portion of each plunger 28 is a slot or recess 32 which receives a hook 34 provided at the inner end of one leg of a connecting arm 33, the end of the aforesaid hook portion 34 cooperating with the end wall of the slot 32 to form stop means limiting extension of the connecting arm 33 outwardly of the casing 20, as shown in Figs. 4, 9 and 10. Surrounding the free end portion of the hook 34 is a compression spring 35 which constantly biases or urges the arm 33 inwardly with respect to the casing 20 toward the position shown in Figs. 2, 3, 5, 7 and 8, wherein the assembly made up of a plurality of the links is contracted to its inner limit.

The connecting arms 33, in the illustrative form shown in Figs. 1 to 11, have their main portions of bifurcated form, the legs thereof being connected at their outer ends by a loop portion, being of unequal length and the longer leg 36 being straight, while the end portion of the other leg 37 is reversely turned back to form the hook 34, described above. The longer or top leg or leg portion is designated 36, and the shorter or rear leg portion is designated 37. Each leg portion 36 is supported for longitudinal sliding movement in a slot 38 extending from end to end of the plunger 28 adjacent the slot 32 in the upper or outer

4

surface of the plunger 28, as shown in Figs. 2 to 5, and 7 to 11. At the opposite side of the plunger 28, a similar slot 39 is provided for supporting the leg portion 37, this slot extending only from the end of the plunger 28 adjacent the wall 23 to the slot 32, as shown in Figs. 7 to 11, inclusive.

The cooperation of the parts is such that when the top plate 22 is secured to the casing, the leg portions 36 and 37 are retained in the slots 38 and 39 respectively by the bottom wall 25 and the top plate 21, while the hook portion 34 prevents outward longitudinal displacement or extension of the arms 33 beyond the position shown in Figs. 4, 9 and 10.

For cooperative, pivotal and interlocking relation with the pair of arms 33 on an adjacent link, a pair of trunnions 40 are provided which trunnions 40 are extensions of the fixed leg portions 41 integrally secured to an end wall 24. The trunnions 40 are laterally spaced with respect to the wall 24 and oppositely directed, since they extend toward one another. The spacing of these trunnions 40 is such that when the plungers 28 are free of manual pressure, as shown in Figs. 3 and 4, the loop portions of the arms 33 are maintained in engagement with the trunnions 40 by the above described compression springs 30, which yieldingly urge or force the plungers 28 apart. As shown in Fig. 5, when manual force is applied inwardly of the link, in opposite directions, to the respective plungers 28, the yielding force of the springs 30 is overcome, and the arms 33 are brought together sufficiently to clear the trunnions 40 for ready and convenient detachment therefrom. In order to attach one link to another, it is merely necessary to apply manual force as shown in Fig. 5 to bring the parts to the position shown therein, then align the trunnions 40 of one link with the space in the loop between the leg portions 36 and 37 of the arms 33 of the other link, and release the manual force applied to the plungers 28, whereupon the parts will take the position shown in Fig. 3. Thus, the trunnions 40 and arms 33 form fixed and movable hinge means on adjacent links yieldingly urged toward locking or interlocking engagement by the plunger spreading springs 30.

Alternatively, if it is desired to secure a closer coupling of the respective links, the trunnion structure 40, 41 may be omitted, and a suitable spaced and located pair of slots 42a (Fig. 11) may be provided in the end wall 24, which slots will have oppositely directed inwardly extending trunnion projections 42, as shown in Fig. 11, which may be engaged by the loop portions of the respective arms 33 when manual force is released from the plungers 28 for this purpose.

A simplified form of the invention is illustrated in Figs. 12 and 13 wherein the casing or frame is generally designated 20a and is of the same general form as the above described frame or casing 20, except that the slot 26a in each of the side walls 22 is narrower than the above described slot 26 while a forwardly or outwardly raised shoulder 28a is provided at the inner end of the plunger 28 to engage that portion of the wall 22 extending above or outwardly of the slot 26a. The plungers 28 terminate inwardly with the shoulder 28a, because, in this construction, it is unnecessary for them to provide support for the connecting arms, since these connecting arms (designated 43) are formed by a substantially M-shaped flat spring member 42. The arms or portions 43 forming the connecting arms are provided with apertures 44 (Fig. 13) for engaging the trunnions 40

and this member 42 has the intermediate V-shaped portion 45 thereof, of substantially the same length as the length of the space between the walls 23 and 24. Thus, three loops are formed in the member 42, two of which engage the inner side or surface of the end wall 24, and one of which engages the inner surface of the end wall 23 to retain the spring member 42 in proper location with respect to the frame or casing 20a. This construction is extremely easy to assemble, since it is merely necessary that the spring member 42 be pushed towards the wall 25 in the space between the inner ends of the plungers 28 or between the shoulders 28a thereof with the portions 43 projecting outwardly through the slots 27.

The construction illustrated in Figs. 14 and 15 is similar to that shown in Fig. 12, except that the intermediate V-shaped portion 45a thereof is of lesser extent than the corresponding portion 45 described above. This abbreviation permits of the insertion of a resilient block (not shown) or a leaf spring member 48 between the wall 23 and this V-shaped portion 45a, whereupon the central part of this portion 45a will be supported on the central portion of the spring member 48 which acts as a yielding knife edge, so to speak. This permits of extension of the arms 43 unequally upon relative lateral movement of adjacent links in expansion of the assembly embodying such a link, since the axis a—a of the apertures 44 (Fig. 14) may move laterally as well as outwardly as, for instance, to the position designated a'—a' in Fig. 15.

When the arms 43 are in the position shown in Figs. 12, 14, and 15, they interlockingly engage the trunnions 40 of a coupled link. In order to disengage or uncouple the links, it is merely necessary to apply manual force to the plungers 28 to move them together, thus bringing the arms 43 together to such extent that they may be removed from the trunnions 40 in the manner generally illustrated in Fig. 5 with respect to the arms 33.

It is to be noted that the outer ends of the biasing leaf spring member 48 are turned back upon themselves to form terminal loops 49 on the spring member which loops 49 are forced outwardly upon compression of the biasing spring 48 (i. e., extension of the arms 43) to exert a snubbing and stiffening effect upon the connecting arms. This prevents undue movement of these arms 43 in extension and contraction, exerting a damping effect thereon.

As an alternative, one plunger 28 may be omitted, and a dummy 28b substituted therefor, this dummy plunger being rigidly secured to or integrally formed with respect to one wall 22. The other plunger 28 is of the form shown in Figs. 12 to 15, and has the shoulder 28a at its inner end in engagement with a flat portion 53 of a generally L-shaped spring member 54. The spring 54 has the other flat portion 55 thereof secured between the wall 24 and a suitable retaining abutment or shoulder 56, as shown in Fig. 16. One of the slots 27 in the wall 23 is omitted and a stationary apertured leg 43a is rigidly secured to the wall 23. This arm 43a, though of the same general form and disposition as the above described arms 43, is laterally unyielding since it is fixed to the outside surface of the wall 23.

From the above description it will clearly appear that connection of a plurality of links of the above described construction is achieved conveniently and easily by a simple manual squeezing operation, the size and extent of the plungers

obviating fumbling, their accessibility obviating the necessity for tools or appliances and the nature of the plunger refracting operation and the location of the plungers preventing accidental uncoupling of the links. Since each of the links may be of this construction, a band, bracelet or wristlet, for instance, may be uncoupled anywhere throughout its length since such uncoupling may be achieved by the uncoupling of any pair of adjacent links throughout the length thereof.

Furthermore, the bracelet, band, or the like may be made expandable by the interposition therein of only one, or more, of the link constructions shown in Figs. 1 to 11 inclusive or in Figs. 15, 14 and 15. In the latter construction (furthermore) unequal expansion at the respective lateral edges of the band is permitted.

It is further to be noted that the plungers 28 may be readily formed of cast or molded metal, non-metallic plastic material or even of wood or other desired materials while the frame or casing may likewise be molded, cast, stamped or coined depending upon the material desired. The rectangular form is likewise merely illustrative and may be varied widely in accordance with aesthetic appearance and design practice.

It is of course to be understood that the above description is merely illustrative and in no wise limiting and that I desire to comprehend within my invention such modifications as are included within the scope of the appended claims.

Having thus fully described my invention what I claim and desire to secure by Letters Patent is:

1. In a bracelet or the like comprising a plurality of links detachably connected in end-to-end relation, a link comprising a casing having fixed transversely spaced inwardly directed trunnions associated with one end thereof, a pair of transversely spaced connecting arms projecting from the opposite end of said casing, means normally yieldingly spreading said arms apart a distance greater than the spacing of the adjacent ends of said trunnions, and means manually engageable and actuatable in opposition to said last named means for moving said arms together sufficiently for disengagement from said trunnions, said last named means comprising at least one plunger extending through a side wall of said casing and normally biased outwardly of said casing.

2. In a bracelet or the like comprising a plurality of links detachably connected in end-to-end relation, a link comprising a casing having fixed transversely spaced inwardly directed trunnions associated with one end thereof, a pair of transversely spaced connecting arms projecting from the opposite end of said casing, biasing means normally yieldingly spreading said arms apart a distance greater than the spacing of the adjacent ends of said trunnions, and means manually actuatable in opposition to said last named means for moving said arms together sufficiently for disengagement from said trunnions, said last named means comprising a pair of similar plungers movable outwardly and inwardly of said casing through said side wall, said plungers extending throughout a major portion of the length of said casing for convenience of manual engagement.

3. The structure defined in claim 2 wherein said plungers support said connecting arms.

4. The structure defined in claim 2, wherein said connecting arms are supported by said plungers for movement inwardly and outwardly with respect to said casing for expansion and

contraction of said bracelet or the like, and means associated with said arms and said plungers for yieldingly resisting extension of said arms for expansion of said bracelet or the like.

5. In a bracelet or the like, a link comprising a casing having top, bottom, side and end walls, trunnions on one end wall of said casing, said trunnions being transversely spaced and directed toward one another, a pair of arms projecting outwardly through the opposite end wall of said casing and having apertures adapted to receive said trunnions, said arms being yieldingly urged apart toward interlocking engagement with the trunnions of an adjacent link when engaged therewith, and manually engageable means for moving said arms together for disengagement of said arms from said trunnions, said last named means comprising a pair of plungers extending from said casing at opposite sides and each engaging one of said arms.

6. The structure defined in claim 5, wherein said arms are formed of resilient material and connected at their inner ends by an integral loop portion yieldingly urging said arms apart toward interlocking engagement with said trunnions when engaged therewith.

7. In a device of the character described, a link comprising a body, fixed hinge means secured to one end of said body, movable hinge means extending from the opposite end of said body, biasing means yieldingly urging said movable hinge means toward a predetermined position wherein it will interlock with said fixed hinge means on a similar link body when engaged therewith to form a hinge connection therebetween, and manually engageable means comprising a pair of opposed plungers projecting transversely from said body and movable inwardly of said body toward one another for overcoming the force of said biasing means and moving said movable hinge means from said predetermined interlocking position to a position facilitating disengagement of said movable hinge means from said fixed hinge means for disconnecting said adjacent links.

8. The structure defined in claim 7, wherein one of said hinge means is yieldingly extensible endwise with respect to said body to provide expansion in an assembly including said link as a part thereof.

9. The structure defined in claim 7, wherein said manually engageable plungers are normally spread apart by said biasing means and normally contractible to overcome the spreading force of said biasing means for moving said movable hinge means positively away from said interlocking position.

10. In a device of the character described, a frame, a pair of opposed plungers extending transversely therefrom, a pair of connecting arms engageable with cooperating means on an adjacent frame for hingedly connecting said frames, means normally maintaining said connecting arms locked to said cooperating means when engaged therewith, said plungers being manually movable toward one another for unlocking said arms for disengagement from said cooperating means.

11. The structure defined in claim 10, wherein said connecting arms are yieldingly extensible for expansion of a structure including embodying said frame, said arms and associated parts.

12. The structure defined in claim 10, wherein said plungers support said connecting arms independently of said frame.

13. The structure defined in claim 10, wherein

said plungers support said connecting arms for yielding extension independently of said frame.

14. In a bracelet or the like, a link comprising a casing, trunnions fixed to one end wall of said casing, said trunnions being transversely spaced and directed toward one another, a pair of arms projecting outwardly through the opposite end wall of said casing and having apertures adapted to receive said trunnions, said arms being yieldingly urged apart, and manually engageable means operable for decreasing the distance between said arms for disengagement of said arms from said trunnions, said last named means including a plunger projecting outwardly through one of the side walls of said casing and engaging one of said arms.

15. The structure defined in claim 7, wherein the arm engaged by said plunger is formed of resilient material and provided at its inner end with an extension fixed to said casing.

16. In a bracelet or the like, a link comprising a casing, fixed trunnions at one end of said casing, said trunnions being transversely spaced and directed toward one another, connecting means adapted for pivotal connection with the trunnions of a similar adjacent link including a pair of transversely spaced yieldingly spread arms extending beyond the opposite end of said casing, and means for moving said arms together for disengagement from said trunnions comprising a pair of plungers projecting transversely from said casing, said arms comprising the extremities of a substantially M-shaped leaf spring, the V-shaped portion of said leaf spring between said arms yieldingly spreading said arms apart and the loop portions of said leaf spring engaging the inner surfaces of the opposite casing end walls for maintaining said leaf spring in position with respect to said casing, and said plungers each having shoulders at their inner ends limiting their movement outwardly of said casing, said shoulders engaging said arms.

17. In a bracelet or the like, a link comprising a casing, fixed trunnions at one end of said casing, said trunnions being transversely spaced and directed toward one another, connecting means adapted for pivotal connection with the trunnions of a similar adjacent link and including a pair of yieldingly extensible transversely spaced yieldingly spread arms extending beyond the opposite end of said casing, and means for moving said arms together for disengagement from said trunnions comprising a pair of opposed plungers projecting transversely from said casing, said arms comprising the extremities of a substantially M-shaped leaf spring, the V-shaped portion of said leaf spring between said arms yieldingly spreading said arms apart, and a leaf spring disposed between said arms and between said V-shaped leaf spring portion and the adjacent casing end wall for supporting said M-shaped leaf spring for yielding extension of said arms unequally from said casing, said last named leaf spring having end portions frictionally engaging said arms upon extension thereof to exert stiffening and snubbing forces thereon, and said plungers each having shoulders at their inner ends limiting their movement outwardly of said casing, said shoulders engaging the outside lateral surfaces of the respective arms.

18. In a bracelet or the like, a link comprising a casing, fixed trunnions at one end of said casing, said trunnions being transversely spaced and directed toward one another, connecting means adapted for pivotal connection with the

trunnions of a similar adjacent link and including a pair of transversely spaced arms extending beyond the opposite end of said casing, a pair of manually engageable plungers extending from opposite sides of said casing, means positively limiting the outward movement of said plungers with respect to said casing, and means yieldingly spreading said plungers apart, each of said arms comprising a member slidably supported by one of said plungers for endwise movement and terminating at its outer end in a trunnion engaging loop, a longitudinal slot in each arm supporting plunger, and a spring in each of said slots connected with an arm and exerting yielding re-tracting force on said arm.

19. In a bracelet or the like of the character described, a link comprising a casing, fixed trunnions at one end of said casing, said trunnions being transversely spaced and directed toward one another, connecting means adapted for pivotal connection with the trunnions of a similar

adjacent link and including a pair of transversely spaced arms extending beyond the opposite end of said casing, a pair of manually engageable plungers extending from opposite sides of said casing, means limiting the outward movement of said plungers with respect to said casing, and means yieldingly spreading said plungers apart, each of said arms comprising a bifurcated member slidably supported by one of said plungers for endwise movement and terminating at its outer end in a trunnion engaging loop, a hook at the inner end of one furcation of each arm movable in a longitudinal slot in the supporting plunger, a spring supported in said slot and engaging said hook and exerting yielding retracting force on said arm, through said hook, said hook engaging an end of said slot upon extension of said arm positively to limit extension of said arm with respect to said casing.
